UNITED STATES PATENT OFFICE.

EDWARD L. MORRIS, OF BOSTON, MASSACHUSETTS.

DESIGN FOR AN INKSTAND.

SPECIFICATION forming part of Design No. 11,951, dated August 17, 1880.

Application filed June 9, 1880. Term of patent 7 years.

To all whom it may concern:

Be it known that I, EDWARD L. MORRIS, of Boston, in the county of Suffolk and State of Massachusetts, have originated and designed 5 a Pattern for Inkstands, of which the following is a full, clear, and exact description, reference being had to the accompanying drawings, making part of this specification.

Figure 1 is a side elevation, and Fig. 2 a 10 horizontal section on line $x x$, Fig. 1, showing a top view of my design.

A represents a hollow base containing an ink-well, B. E is a miniature well-curb surrounding the base. C C represent an old-fashioned well-sweep and post in miniature, surrounding the base. D is a bucket hanging from the well-sweep and containing a sponge, which aids to complete the resemblance to 15 "the moss-covered bucket which hung in the well." An opening, H, through the top of the base under the well-curb E imitates the mouth 20

of a well. The top of the ink-well B or a collar surrounding the top is decorated to imitate a tub or cask set in the ground.

F F are pen-racks upon the sides of the base 25 A, and G G (shown in Fig. 2) are pen-grooves upon the top of the base A.

What I claim is—

1. A design for an inkstand, consisting of a base, A, surmounted by a miniature well-curb, E. 30

2. A design for an inkstand, consisting of a base, A, surmounted by a miniature well-curb, E, and miniature well-sweep, post, and bucket C C D. 35

3. A design for an inkstand, consisting of a base, A, surmounted by a miniature well-curb, E, and imitation tub or cask B.

EDWARD L. MORRIS.
